COLLAR SUPPORT

Albert P. Herrlinger, Cincinnati, Ohio, assignor
to The Herrlinger Paper Co., Cincinnati, Ohio,
a corporation of Ohio

Application December 19, 1932, Serial No. 647,857

1 Claim. (Cl. 223—18.6)

My invention relates to a new and improved collar support of the type which is positioned within the neck band for supporting the collar in an upright position.

5 In laundering shirts with collars attached it is necessary in order to prevent crushing of the collars, to reinforce the collars prior to packing the shirts in a bundle for delivery. My invention contemplates an inexpensive collar support which 10 grips the inner band of the collar and is so constructed to prevent the support from jumping out of place. The support, which is preferably made of flexible pasteboard, is provided with points on its lower face which grip the shirt and 15 prevent the support from moving forwardly out of position which is the common fault of other supports of a similar nature that have a smooth lower edge.

The object of my invention is to provide a 20 collar support having a lower edge provided with a central point and points intermediate the lower edge of the support. A further object is to provide the ends of the support with receding edges whereby a point is formed in the end of the support to more firmly grip the band of the collar.

25 My invention will be further readily understood from the following description and claim and from the drawing, in which latter:

Fig. 1 is a perspective view of a shirt with my 30 collar support in the place looking from the rear of the shirt.

Fig. 2 is a cross-section of the same, taken in the plane of the line 2—2 of Fig. 1, and;

Fig. 3 is a plan view of the collar support.

35 I have shown my improved collar support in connection with a shirt 11 provided with a collar 12 attached thereto. My improved support comprises a blank 13 which is preferably cut from a piece of flexible pasteboard although any other 40 suitable flexible material may be used. The lower edge of the collar support is provided with a central point 14 and teeth 15 while the upper edge is cut in straight lines forming tangents to an arc which makes the upper edge 16 substantially of an arcuate shape. The points 15 are 45 formed in the bottom edge of the collar support blank 13 by angular cut-outs therein. Said cut-outs are formed by making straight cuts from the point 14 towards the ends of the blank at a slight inwardly slanting angle from the bottom 50 edge thereof and then making intersecting cuts from the points 15 at a considerably wider angle. This results in the points 15 being slightly undercut. Thus the two points 15 and the central point 55 14 form a three point support for the central

portion of the device when the same is in position within the neckband. The ends 17 of the support are provided with points 18. In placing the support within the collar of a shirt the points 18 grip the shirt at points 14 and 15 resting on the back of the shirt 11. The upper edge 16 of the support extends slightly above the collar at the forward portions thereof to protect the upper edge of the collar when a plurality of articles are wrapped together in a bundle. As is readily apparent from Figure 2, the portion that extends above the front of the collar is in the nature of an arcuate abutment above the three points on the bottom edge. When the shirts are packed in bundles, the pressure incident to such packing is first borne by this abutment which causes the support 13 to rock forwardly slightly while at the same time, the points 15 and 14 are forced downwardly into engagement with the back of 20 the shirt.

Any tendency on the part of the support to urge 25 itself forward with a tendency of creeping out of the collar band is arrested by the points 15 contacting the back of the shirt and preventing 30 the support from creeping out of its position in the collar. As the points 15 have an inward set, they not only resist forward creeping, but also resist spreading movement of the ends of the support 13, and, moreover, they also prevent endways movement of the device,—as such movement in either direction will be resisted by one or the other of the points 15. While the points 18 on the ends of the support 13 likewise resist such endways movement, it is obvious that they 35 do not resist spreading movement of the ends that occurs when pressure is applied to them or to the support, and which movement tends to occur because of the natural inward slant of the support as it is used.

Having thus fully described my invention what 40 I claim as new and desire to secure by Letters Patent, is:

A collar support for shirts comprising a strip 45 of flexible material, the lower edge thereof providing a medial friction point, the stock of said edge on either side of said point being recedingly cut out toward the upper edge and adjacent ends, said cutouts terminating to provide forwardly extending friction points intermediate said first 50 point and said ends, the rear lower portions of said strip edge being plane and adapted to rest upon the shirt back within the neckband of the collar thereof, said medial point and second named points providing a three point support for 55

the forward part of the strip, the upper edge of the strip having at least the intermediate portion thereof cut to define a plurality of tangents to the same arc whereby when the strip is bowed certain of said tangentially cut portions of said upper edge will define an arcuate abutment portion disposed above the upper edge of the collar at each frontal side thereof and intermediate the

central point of the lower edge and the respective forwardly extending points thereof, whereby pressure upon said arcuately curved abutment portion tends to rock the bowed strip forwardly slightly to effect digging of all of said points into the back of the shirt so as to prevent shifting of said strip.

ALBERT P. HERRLINGER.
